UNITED STATES PATENT OFFICE.

SIGOURNEY WALES, OF CAMBRIDGE, MASSACHUSETTS, ASSIGNOR TO WILLIAM C. HOWARD, OF NEW YORK, N. Y.

PENCIL-CLASP.

SPECIFICATION forming part of Letters Patent No. 289,476, dated December 4, 1883.

Application filed March 19, 1883. (No model.)

To all whom it may concern:

Be it known that I, SIGOURNEY WALES, of Cambridge, in the county of Middlesex and State of Massachusetts, have invented certain new and useful Improvements in Pencil-Holders, of which the following, taken in connection with the accompanying drawings, is a specification.

My invention relates to a pencil-holder to be attached to a garment of the user; and it consists of a spring tube or socket so constructed as to form one jaw of a clasp, in combination with a second jaw pivoted thereto and exteriorly thereof, and provided with a curved spring-arm which projects through an opening into the interior of said socket, and has formed at its upper end a catch in the form of a roll or coil of the metal, which snaps over and engages with the upper end of the wall of said socket when the jaws are forced together upon the material to which they are to be secured, and thus firmly secures the grip of the jaws upon the material against accidental release.

Figure 1 of the drawings is an elevation of a blank cut from thin sheet metal, from which the socket portion of the holder is to be formed by bending and swaging it into the shape illustrated in Figs. 2, 3, 4, and 5, which are respectively a front elevation, a side elevation, a rear elevation, and a transverse section on line $x-x$ of the finished socket. Fig. 6 is an elevation of the blank cut from thin sheet metal, from which the movable jaw of the holder is to be formed by bending and swaging to the shape illustrated in Figs. 7, 8, and 9, which are respectively a side elevation, an end view, and a transverse section on line $y-y$. Fig. 10 is a side elevation of the holder complete. Fig. 11 is a rear elevation of the same. Fig. 12 is a vertical section on line $z-z$ on Fig. 11. Fig. 13 is a transverse section on line $v-v$ on Figs. 10, 11, and 12; and Fig. 14 is a central vertical section illustrating the application of my improved holder to the upper edge of a vest-pocket welt, with a pencil in position therein.

The blank from which the socket A is to be formed is provided with the fingers a a , and has cut through its center the opening b , and

in the strip of metal c , at each side of said opening, has formed a hole, c' , and has formed upon the lower end of the central downward projection, d , a series of pointed teeth, d' , and upon each side of said projection a single tooth, d'' , all of which teeth, with the ears in which the holes c' are formed, are bent at right angles to the main body of said blank in one direction, while the said main body is rolled or bent in the opposite direction into the form of a tube, the projection d remaining substantially flat or uncurved, as shown in Figs. 4 and 5.

The blank from which the movable jaw is formed is provided with the broad blade e , the narrower tongue e' , and the small lateral projections e'' e'' , which serve as trunnions, by which said jaw is pivoted to the socket A, said trunnions having bearings in the holes c' c' . The bottom and two vertical side edges of the blade e are bent or swaged to form a shallow recess, the tongue e' being at the same time bent, as shown in Fig. 8, to form at its upper end the roll or bead e^3 , and give it a curve between said roll and the blade e , as shown, which curved portion of the tongue e' , when in position in the completed holder, serves as a spring, by the partial straightening of which the bead e^3 is permitted to pass over the upper edge of the socket A at f , and holds it firmly in such position when allowed to assume its normal position.

In applying this holder to a garment—say the upper edge of a vest-pocket welt, as illustrated in Fig. 14—it is only necessary to open the jaws of the clamp by pressing the upper end of the tongue e' inward to disengage the bead e^3 from the upper edge of the socket A, place the pocket-welt between the jaws d and e , and then press upon the inner curved surface of the tongue e' until the bead e^3 snaps over the top of the socket A, when the teeth d' and d'' will have been forced into the cloth and pressed it into the recess of the jaw e , which is of somewhat greater area than the jaw d . When the pencil B is placed in the socket, its walls and the fingers a a yield to accommodate the size of the pencil, and press thereon to hold it in place, and the pencil pressing upon the tongue e' prevents any pos-

sibility of accidental unclasping of the holder, and particularly is this the case when entering and withdrawing it, and it is obvious that when the pencil is out no action to disengage the 5 clasp is probable.

What I claim as new, and desire to secure by Letters Patent of the United States, is—

A pencil - holder composed of a yielding-sided tubular socket slotted at its rear, and 10 provided with a toothed jaw or surface, and the bearings $c' c'$, and a movable jaw pivoted in the bearings $c' c'$, with its upper portion inside of the tubular socket and its lower por-

tion outside thereof, and provided at its upper end with the roll or bead c^3 , adapted to engage with the upper end of the tubular socket, substantially as described.

In testimony whereof I have signed my name to this specification, in the presence of two subscribing witnesses, on this 17th day of March, 20 A. D. 1883.

SIGOURNEY WALES.
